FIG. 1.

FIG. 2.

FIG. 3.

FIG. 4.

FIG. 5.

FIG. 6.

FIG. 7.

FIG. 8.

FIG. 3 is a top plan view thereof;

The stippled areas represent contrast in surface texture. The rear elevational view is the same as the view shown in FIGURE 1 and the other side is the same as the view shown in FIGURE 2.

I claim:

The ornamental design for a bottle, substantially as shown and described.
